[57] **CLAIM**

The ornamental design for a combined monitor screen, video tape recorder and video camera, as shown and described.

DESCRIPTION

FIG. 1 is top, rear and right side perspective view of a combined monitor screen, video tape recorder and video camera according to our design;

FIG. 2 is a top, front and left side perspective view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a front elevational view thereof;

FIG. 9 is a top, rear and right side perspective view with the monitor screen and video tape recorder rotated 180° relative to the video camera;

FIG. 10 is a top, front and right side perspective view of the video camera with the combined monitor screen and video tape recorder rotated 180° as in FIG. 9;

FIG. 11 is a top, front and left side perspective view of the combined monitor screen, video tape recorder and video camera with the video screen cover in an open position; and, FIG. 12 is a view similar to FIG. 11 with the cover removed.
